UNITED STATES PATENT OFFICE.

JOHN W. MAWBERRY, OF WORCESTER, MASSACHUSETTS.

ATTACHMENT FOR BOOKS AND THE LIKE.

1,109,345.

Specification of Letters Patent.

Patented Sept. 1, 1914.

Application filed April 7, 1913. Serial No. 759,349.

To all whom it may concern:

Be it known that I, JOHN W. MAWBERRY, a citizen of the United States, residing at Worcester, in the county of Worcester and 5 State of Massachusetts, have invented a new and useful Attachment for Books and the like, of which the following is a specification.

Although capable of general use, this invention is particularly adapted and especially designed for use on comparatively large and heavy books which ordinarily are kept on a desk or table and are turned to different positions thereon in the ordinary 15 course of business; as for example, ledgers, hotel registers, and index and record books of various kinds. It has been found convenient to make such books of large size, and in order to turn them into the positions in which they are used, especially to reverse them, as is frequently necessary, they have been mounted upon turn-tables 20 of various kinds. When not so mounted, it has been found necessary to provide them with very durable and expensive bindings.

The principal object of this invention is to provide a simple and inexpensive construction for application to books for these general purposes so that they can be turned 30 readily to any desired position on a plane supporting surface, without necessitating the use of a turn-table or expensive binding.

The invention also involves certain improvements in details of construction as will 35 appear hereinafter.

Reference is to be had to the accompanying drawings, in which—

Figure 1 is an end elevation of a book constructed in accordance with this invention; Fig. 2 is a similar view showing the book opened and ready for use; Fig. 3 is a sectional view on enlarged scale through the center of one cover of the book; and Fig. 4 is a plan of the attachment which is shown 45 in the other figures.

The invention is shown as applied to a record book or the like, 10 having the usual cover 11. A convex projection 12 is located on one of the cover leaves under the center 50 of gravity of the book as it lies on its side as in Fig. 1. This projection is sufficiently thick to support the book on a plane surface, and to hold the main body of the book high enough from said plane surface so that 55 its edges and back do not touch the same when in the position shown in Fig. 1. Thus

it constitutes a single supporting means for the book in that position, and yet when the book is open, as shown in Fig. 2, it does not interfere with the position of the parts of 60 the book or affect the opening of the book at any desired point. It will be seen that the book being balanced, it is a simple matter to turn it around on this center, end to end or to any desired position. In this way no 65 turn-table is required for this purpose, and as the edges and back of the book do not come into contact with the surface on which the book rests, the entire wear, due to turning, will come on the bottom of this projection. It will be understood, of course, that 70 this projection can be originally formed as a part of the front or back cover of the book and made integral with it. In that case the material with which the book is bound, as 75 for example, leather, buckram, or other sheet material 13 can be brought around under the projection in the process of binding and form the surface on which the book is turned. However, another convenient way 80 of arranging this is shown in Figs. 3 and 4 in which the cover 11 is made in the usual way, and the projection is formed of a body 14 preferably of the material of which the cover is made. It can be made of papier 85 maché, wood, or other material. It is made plane on one side and convex on the other. The plane side is provided with a metal plate 15 into which screws 16 set into the cover are screwed for the purpose of holding it in 90 position.

A cover-sheet 17 is provided of the same material of which the sheet 13 is made, or if desired of a more durable material. This is covered over the convex side, brought 95 around over the upper edges, and can be cemented or glued to the surface of the sheet 13 if desired. This sheet extends over the ends of the plate 15, this plate itself when screwed up in position holding it in 100 place. In this form of the invention it will be obvious that the sheet 17 which receives most of the wear can be made of material of any desired durability, so that the life of the binding of the book can be materially prolonged over that class of books which lie 105 flat on a desk or table, and have to be turned around thereon.

It is to be observed also that this attachment when made separately from the book, 110 as shown, can be sold separately as an article of manufacture. It can then be applied

directly to a book or the like already in use, or in fact to any other article which has to be turned on a center.

The invention is particularly applicable for use on hotel registers, bank entry books, and index and record books for use in various offices where a clerk makes entries on one side of a desk or table and turns the book around for the public to examine or make entries from the other side thereof. It will be seen, moreover, that only a comparatively small projection need be made for this purpose, and that it does not add materially to the cost or weight of the book. At the same time, it does not have any effect on the book when opened and does not prevent the book being placed in a case in the ordinary way.

Although I have illustrated and described only certain forms in which the invention can be carried out, I am aware of the fact that many other modifications can be made therein by any person skilled in the art and that it can be used for many purposes without departing from the scope of the invention as expressed in the claims. Therefore I do not wish to be limited in these respects, but

What I do claim is:—

1. The combination with a book having a cover, of an attachment for the cover having an inner flat surface and an outer convex

surface, and means carried by the cover for securing the attachment thereto.

2. As an article of manufacture, a book having a cover provided with small outer circular convex portion having its thickest part under the center of gravity of the book when the book is lying on its side.

3. As an article of manufacture, a supporting attachment having a convex surface, a flat top plate, and a cover for the attachment over the convex surface and extending over the outer edges of the plate.

4. As an article of manufacture, a book having a projection substantially at the center of one cover thereof and extending outwardly therefrom, the outer surface of such projection being convex and constituting a support having a small supporting area, whereby when the book is laid on its side with said projection underneath only the center of said projection will come into contact with the supporting surface and the book can be turned readily on said center as a pivot.

In testimony whereof I have hereunto set my hand, in the presence of two subscribing witnesses.

JOHN W. MAWBRY.
